(57) **CLAIM**

The ornamental design for a combined flow stop and tubing guide, as shown and described.

DESCRIPTION

FIG. 1 is a front top perspective view of the flow stop and tubing guide of the present invention showing our new design with the phantom lines depicting environmental structure and forming no part of the claimed design; FIG. 2 is a front elevational view of the flow stop of FIG. 1 shown at an enlarged scale;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof;

FIG. 8 is a top end view of the tubing guide of the present invention shown at an enlarged scale.

FIG. 9 is a front elevational view thereof;

FIG. 10 is a side elevational view thereof; and,

FIG. 11 is a bottom plan view thereof.

The stop shown in FIGS. 2 through 7 and tubing guide shown in FIGS. 8 through 11 are depicted separately for clarity of illustration.
